UNITED STATES PATENT OFFICE

WILLIAM F. HELMOND, OF WEST HARTFORD, CONNECTICUT, ASSIGNOR TO UNDERWOOD
ELLIOTT FISHER COMPANY, OF NEW YORK, N. Y., A CORPORATION OF DELAWARE

ELECTRIC SWITCH

Original application filed December 11, 1926, Serial No. 154,107, now Patent No. 1,835,776, dated December 8, 1931. Divided and this application filed July 14, 1930. Serial No. 467,726.

This invention relates to typewriting machines, and more particularly to means for returning the typewriter-carriage by power.

A finger-piece at the keyboard controls an arm of a novel electric switch, said arm being thrown into circuit-making position by a spring which is controlled by a pawl that is so connected to the finger-piece that varying blows upon the finger-piece result in the same action of the switch-arm, energizing the motor.

A worm-shaft of a motor-drive effects an engagement of clutch-members, whereupon a carriage-return rack first effects the line-spacing, and then the return of the carriage. Means are carried by the carriage to throw out the switch-arm at the completion of the return of the carriage, or at any intermediate position.

The mechanism is arranged to be readily attached to a standard Underwood typewriting machine with a minimum of changes and additions.

The switch includes a circuit maker and breaker, in the form of a swinging contact-arm, mounted and controlled in such a manner to be free from sparking, noiseless in action, and capable of rapid manipulation. Said keyboard finger piece or key engages

a slide carrying a by-pass pawl, the latter coacting with the contact-arm to first move said arm rearwardly against a spring, tensioning the spring which becomes effective on the further movement of the slide and 35 by-pass pawl, to release the arm, and then under the force of the released spring tension said arm is thrown into contact with the switch, and thereby closes the circuit.

By the use of this by-pass mechanism the operator may hold the finger-key depressed, while the contact-arm may be disconnected by any means, or by the returning carriage and its connections. The finger key must be returned and the by-pass pawl resume its normal position before the repeating of a switch-closing action can take place. This becomes important in a short return stroke of the carriage, since in such work the operator may have pressed down the key, and

the switch may not have been released in some cases.

The disconnection of the contact-arm from the switch by the return of the carriage, to open the circuit, is effected by a 55 stop-member on the carriage which engages a dog carried by the right-hand marginal stop, said dog coacting with a rocking switch-release frame, one end of which carries a depending link, effective to throw 60 out the contact-arm of the switch, at intermediate stations. The contact-arm is released to open the circuit for the final or "0" position of the carriage, by the marginal stop-release lever that is mounted on the car- 65 riage.

One feature of the present invention is the provision of a switch-mechanism operated by a finger-key associated with means for preventing a repeat action of the switch- 70 contact-arm of the switch-mechanism, while the operator holds the finger-key depressed. The closing of the circuit for the second cycle of operation can take place only after the return of the finger-key. 75

This application is a division of my application, Serial No. 154,107, filed December 11, 1926 (now Patent No. 1,835,776, dated December 8, 1931.)

Other features and advantages will here- 80 inafter appear.

group, showing the component parts of the switch-contact-arm.

Figure 8 is a perspective view, in group, showing the contact-members and their connecting leaders.

Figure 9 is a sectional view (enlarged) of the contact-arm assembled.

Figure 10 is a longitudinal sectional view (enlarged) of the switch-block.

10 Figure 11 is a detail perspective view of the switch-block and contact members.

Figure 12 is an under side view of the switch-block and the connecting leaders to the contact-arms.

15 In the practice of my invention, a carriage 10 of an Underwood typewriting machine in which the invention is embodied is supported in the well-known manner to travel along the machine for letter-spacing 20 on a rear rail (not shown) and a front rail 11 secured on the main frame 12.

25 For returning the carriage there is provided a carriage-rack-bar 13 which meshes with a pinion 14 driven by a motor 15, and suitable clutch-mechanism is interposed between the motor and pinion, so that the pinion may be either connected to the motor or disconnected therefrom.

30 The motor 15 is located at the rear of the machine and is attached to a bracket 16 of a housing 17 supported on the main frame 12.

35 A switch 18 is located at the left on a bracket 19 of frame 12, above the keyboard and below the supporting rods of the carriage-marginal-stop-members. A connection from below is made by a key-lever 20 and slide-member 21 to throw in a pivoted switch-contact-arm 34 to close the motor-circuit.

40 The switch 18 includes a body or frame 23 having an arm 24 held to bracket 19 of frame 12 by screws 25. The body 23 has a guide bracket 26 fastened by a screw 27.

45 The bracket 26 is bent to provide a wall 28, in which there is a guide slot 29 to receive the end of the slide 21, which is further guided for movement by a screw-and-slot connection 30 at the lower part of the switch-body 23. Below the frame 23 the slide is bent to make contact with the inner end of the key-lever 20. The upper end of the slide has a shouldered portion 31, between which and the inner side of wall 28

50 a spring 32 is held, and provides for a return motion of the slide after its upward stroke effected by key-lever 20. Bracket 26 extends down and carries a pivot-screw 33 on which is pivoted the switch contact-arm 34, in position to be thrown into contact with a pair of contact-members 35 and 36 on a block 37 of insulation.

55 The switch contact-arm 34 is not directly moved into engagement with the contact-members 35 and 36. A spring actuator 38

is employed and operated by the slide 21. For this purpose the slide has an extension 39 carrying a by-pass pawl 40, the end of which engages a wing 41 of the switch contact-arm 34. Normally the switch contact-arm 34 hangs downward (Figure 4), and the slide 21 in its lowermost position with the by-pass pawl thereon engages the wing 41 on the switch contact-arm 34 and on the upstroke of the slide 21 the spring actuator 38 is forced rearwardly, as in Figure 5 (broken lines), tensioning the spring actuator by the rearward action of the switch-arm, which engages a hooked end of the spring actuator 38 and is carried rearward therewith. When the slide 21 approaches the end of its upward stroke, imparted by the key-lever 20, the by-pass pawl passes clear of the wing 41 on the switch-arm, the tensioned spring actuator 38 is released, and the arm 34 is thereby thrown into contact position between the contacts 35 and 36.

The extension 39 of the slide 21 extends upward, and the top end has a screw 42 around which is coiled a spring 43, one end reaching downward into an opening of the by-pass pawl 40 to urge the pawl toward the wing 41 of switch-arm 34, and against a stop 44 on the slide 21. The other end of spring 43 is caught over the switch-arm 34, holding it lightly against the hooked end of the spring actuator 38, thereby preventing the arm from vibrating or jarring into contact or sparking relation with the switch-contact-members 35 and 36 when the slide 21 is in its normal position. Spring 43, being mounted on slide 21, travels with the same, thus removing the tension on switch-arm 34, when the switch is operated and permits the switch-arm to travel unencumbered by tension of spring 43. In other words, spring 43 holds down the switch-arm only when slide 21 is in normal position.

The spring actuator 38 of suitable wire fastens under the screw-head 27 of the bracket 26 by a loop in the spring, both ends of the wire passing into a perforation of the bracket 26, thereby holding the loop from spreading under the screw-head, and forming a fulcrum-point for the tensioning of one end of the spring actuator when being forced backward by the by-pass pawl. The spring actuator 38 in its normal position forms a stop for the return of switch-arm 34 when the arm is out of contact.

The switch-arm 34 (Figures 8 and 9) is insulated from the body of the switch 23 by providing the arm 34 with contact-portions 45 and 46 insulated from the arm itself by non-conductive washers 47 and 48, the portion 45 having a head and a stem passing through washer 47, the latter having a reduced part fitting in opening of arm 34, the washer 48 fitting on reduced part of washer 47 and the contact 46 on stem of contact 45.

held together as in Figure 9 by heading over the stem of contact 45. Insulated block 37, to which the contact-members 35 and 36 are attached for engagement with the arm 34 to close the line-circuit, is provided with a head 49 wherein is located a pair of circuit-line connecting bushings 50 held by set-screws 51. The bushings 50 are threaded to receive binding screws 52 that serve as terminals to attach line wires. Leaders 53 and 54 are located below the surface at the under side of the block 37 in recesses or channels 55, one end of the leaders being held to the bushings 50 by screws 56 and carried back through the channels 55 to the opposite end of the block 37 to a similar head perforated to receive a flanged bushing 57 of non-conductive material. The leaders 53 and 54 have bent offset portions also perforated to receive the bushing 57. The leader 53 has its bent offset end folded close to the top of the block 37, on top of which is located the contact-member 35, the position of which will be in a plane with one side of the pivoted contact-arm 34. The leader 54 is similarly bent, but provides room between the bent portion for an insulating spacer 58 of such thickness as to provide sufficient space for the proper entrance of the contact-arm 34 between the aforesaid member 35 and the contact-member 36 to engage with the opposite side of the arm 34 to make the circuit connection. The contact-member 36 lying on top of the leader 54, by a screw 59 passing through the perforated parts of leaders 53 and 54, the contact-members 35 and 36, and the spacer 58 into the body of the switch-frame 23, holds the block 37 and parts together. An additional screw 60 to hold the block to the frame 23 is located at the opposite end of the block, passing between the leaders into the frame 23.

The key-lever 20 for operating the slide 21 is preferably mounted on the same pivot center as that of the lock-release lever-shaft 45 61 of the typewriter on the left side of the machine. The lock-release lever-shaft 61 is shortened and the pivot-screw is threaded into the frame 12, and a reduced diameter of the screw passes through the hub of the key-lever and into the end of the lock-release lever-shaft, thereby holding the key-lever in its pivoted position. A flat spring 62 holds the key-lever in its idle position against the frame, as at 63, that is, with the bent end 55 that engages the slide 21 down and clear of the slide.

From the foregoing it will be seen on the depression of the key-lever 20, the slide 21 with the by-pass pawl thereon is actuated to effect contact between the contact-members 35 and 36 by pivoted contact-arm 34, closing the motor-circuit. Upon the return of the carriage, the switch-arm 34 is released from the contacts 35 and 36 as the carriage reaches the end of its travel, either at the final stop

or at stops provided by the usual shiftable right-hand marginal-stop-member 64. The latter is mounted on the usual rod 65 of the machine, which has a pivoted dog 66 thereon with a cam-projection 67 on its top engaged by a lug 68 on the carriage to throw the front of the dog downward, which front end 69 rides on a rail of a switch-release frame 70. The latter is mounted to rock on the rod 65, on a pair of corresponding arms 71 extending forward, one at each end of the rail, and an arm 72 reaching rearward in position above the switch. A link 73 is pivoted at 74 to the arm 72 and extends down, the free end entering the switch-frame 23, passing into a slot 75 in the wall 28 of the bracket 26. The end of the link is in position to engage the switch-arm 34 at the top thereof, on the rocking of the frame to throw the arm 34 out of contact with the members 35 and 36. The dog 66 may be turned over on its pivot to be out of the path of the lug 68 on the carriage, and the carriage will then travel to the full or home position. At this final stop position, the switch-release frame 70 is rocked by the bent end 76 of the right-hand marginal-release lever 77, engaging a cam-projection 78 formed on the end of the rail of the switch-release frame, which rocks the frame, and, as before, throws out the arm 34. To return the frame 70 to normal position, and the link 73 clear of the switch-arm 34, a spring 79, coiled about the rod 65, rocks the frame back, the rail of which engages the main frame 12 as a stop.

Briefly stated, the operation of the mechanism is as follows: On depression of the type-keys the carriage moves step by step, actuated by the usual spring. When the end of the line is reached, the operator depresses the carriage-return key 20. This lifts the slide 21 of the switch, and, through the by-pass pawl 40, shifts rearwardly the switch contact-arm 34 against spring 38. At a certain point in the slide travel, the by-pass pawl releases the arm 34, and the spring 38 throws the arm into circuit between the contact-members 35 and 36, whereupon the motor is set in motion and the carriage returned to a predetermined stopping position. At this time, the carriage is stopped at a right-hand marginal-stop position, and the lug 68 on the carriage will engage dog 66, the latter engaging the rail of the switch-release frame 70, rocking it downward; and the link 73 thereon engaging the switch contact-arm and forcing it out of its closed-circuit position, whereupon the motor stops. The same operation takes place when the carriage returns to its initial or "0" position, except that the cam 78 on the switch-release frame is engaged by the bent end 76 of the marginal-stop release lever 77 instead of the dog 66 on the marginal stop.

Variations may be resorted to within the scope of the invention, and portions of the improvements may be used without others.

Having thus described my invention, I claim:

1. An electric switch including a normally ineffective swingable contact-arm, a normally untensioned spring, an operating key, means operated by said key to swing said arm against said spring to tension the latter, and a trip to break the connection between said means and said arm to permit the tensioned spring to swing the contact-arm to effective position.
2. An electric switch to open and close a motor-circuit, including a pivoted switch-arm, a switch-arm operating spring, a key-actuated trip operable to swing said arm to tension said spring, and then release said arm to enable the spring to effect a quick movement of said arm to effective position, and means dependent upon the functioning of the motor, for causing the arm to open the switch.
3. An electric switch including a pivoted contact-arm, a normally ineffective spring, a key, a slidable member operated by said key, and a member pivoted upon said slide and effective upon operation of said slide to swing said switch-arm to cause it to tension said spring, said arm being self-releasing from said pivoted member, to permit said spring to snap said arm to effective position.
4. An electric switch including a pivoted contact-arm, a normally ineffective spring, a key, a slidable member operated by said key, and a trip mounted on said slidable member effective during the initial movement of said key to swing said switch-arm and cause the arm to tension said spring, and effective upon further depression of said key to release said arm and permit said tensioned spring to swing said arm to effective position.
5. An electric switch to energize a motor for returning the carriage of a typewriting machine, said switch including a pair of terminals in the form of clamping jaws, a pivoted switch-arm to be moved into and out of engagement with said jaws for making and breaking the electric circuit, a normally ineffective switch-arm operating spring, a key, a slidable member operated by said key, a latch carried by said member, and means to cause said latch to swing said arm against said spring to tension the same, said means including an automatic trip to release said arm and permit said spring to impart a swinging movement to said arm of sufficient momentum to cause said arm to enter the clamping jaws of said terminals.
6. An electric switch for energizing a motor to return the carriage of a typewriting machine, including a key, a slide operated by said key, a pawl carried by said

slide, a switch-arm for making and breaking an electric contact, means on said arm to co-operate with said pawl to swing said arm during the initial movement of said key, and a normally untensioned spring, said spring being tensioned during the initial swinging of said arm, said arm being self-releasing from said pawl to permit said tensioned spring to swing said arm from ineffective to effective position.

7. An electric switch for energizing a motor to return the carriage of a typewriting machine, including a key, a slide operated by said key, a pawl carried by said slide, a switch-arm for making and breaking an electric contact, a projection on said arm to co-operate with said pawl to swing said arm during the initial movement of said key, and a normally untensioned spring, said spring being tensioned by said arm during the initial swinging of said arm, said arm being self-releasing from said pawl to permit said tensioned spring to impart a fast swinging movement of said arm in the reverse direction for making the electric contact.

8. A normally open electric switch to close a motor-circuit, including a normally idle pivoted switch-closing arm, a normally idle spring to swing said arm to close the circuit, a key, a trip driven by said key to retract said arm to tension said spring, means being provided to release the trip from the arm at the key-stroke, and means being also provided, dependent upon the functioning of the motor, for retracting the arm to open the switch.
